OIL BURNER

Warren H. De Lancey, Springfield, Mass., assignor
to Gilbert & Barker Manufacturing Company,
West Springfield, Mass., a corporation of Mas-
sachusetts

Application October 24, 1939, Serial No. 301,014

9 Claims. (Cl. 158—76)

This invention relates to improvements in burners of oil or other fluid fuel susceptible of use therein.

The invention has for one object the provision of a burner having means, whereby the shape of the flame may be varied over a wide range and made to fit fireboxes of various shapes and sizes.

More particularly, the invention has for an object to provide a plurality of air directors, some of which direct the air to the flame with a whirling motion and tend to broaden the flame, and others of which direct the air to the flame in a direction longitudinally thereof, tending to elongate the flame.

The invention also has for an object to provide easily and conveniently operable means for controlling the air supply entering through the aforesaid directors whereby the proportion of air that is whirled around the flame and the proportion of air that is directed forwardly of the flame may be varied. By properly adjusting the controlling means, the shape of the flame may be varied from a long, narrow flame of nearly pencil-like shape to a short, wide flame of substantially the shape of an umbrella.

The invention also has for an object the provision of a barrel-like air head having in its periphery two circular series of slots—one series having associated therewith deflectors for the purpose of whirling the air around the axis of the flame and the other series having radial slots only.

The invention also has for an object the provision, within the aforesaid barrel-like head, of a partitioning means to keep the whirled air and forwardly directed air separated until they are about to encounter the flame.

The invention also has for an object to provide a novel mounting of the air-head—including also its control valves, the oil nozzle and ignition electrodes—for convenient removal from the rear end of the burner tube.

These and other objects will best be understood as the detailed description proceeds and they will be pointed out in the appended claims.

The invention will be disclosed with reference to the accompanying drawings in which,

Fig. 1 is a rear elevational view of a burner embodying the invention,—the hood thereof being shown in section;

Fig. 2 is a sectional elevational view thereof, taken on the line 2—2 of Fig. 1;

Fig. 3 is a sectional plan view taken on the line 3—3 of Fig. 2;

Figs. 4 and 5 are cross sectional views taken on the lines 4—4 and 5—5, respectively, of Fig. 2;

Figs. 6, 7 and 8 are fragmentary cross sectional views taken on the lines 6—6, 7—7 and 8—8, respectively of Fig. 2; and

Fig. 9 is a fragmentary bottom plan view with the air tube shown in section to reveal the operating means for the air valves.

Referring to these drawings; the burner includes a supporting frame, comprising a vertically-disposed member 10 (Fig. 1) supported in a manner to permit vertical adjustment from two posts 11, which in turn are fixed to a base plate 12. This member 10 is approximately rectangular in shape and supports along its upper edge and along its two side edges a hood 13, which with the member forms an enclosure (Fig. 2) for the motor, oil pump and transformer. A sheet metal member 14, upstanding from base 12 and fixed thereto along its rear edge and both side edges, cooperates with the hood to more nearly complete the aforesaid enclosure.

The fan housing is formed as a part of the supporting member 10. The latter has a deep recess (Fig. 2) in its front face surrounded by a marginal wall 16 of the shape best shown in Fig. 6 and closed at the back by a flat back wall 16. The recess is closed at the front by a thin, sheet-metal plate 17, set into the member 10 as shown in Figs. 2 and 3 and secured thereto by a series of screws 18 (Fig. 1). The recess forms the fan housing 19 and an approximately cylindrical connecting chamber 20 which communicates with, and virtually forms a part of the air tube of the burner. The plate 17 has an upper circular opening 21 therein, forming an inlet to the fan housing 19, and a lower tubular part 22 in which is fixed the inner end of the cylindrical air tube 23 of the burner.

The fan rotor is shown at 24 in section in Fig. 2 and it is direct-driven from an electric motor 25, which also drives an oil pump 26. The back wall 16 has a circular opening 27 therein to admit the fan rotor. The motor is supported from the back wall 16, preferably by a resilient, shock-absorbing mounting. For example, a substantially semi-cylindrical cradle 28 (Fig. 1) which encompasses the lower half of motor 25, supports the latter by means of rubber blocks 29. The cradle has two lugs 30 which are clamped by cap screws 31 against the back wall 16. Each rubber block 29 has fixed thereto two metal plates 32 and 33, one on each side thereof. The plate 32 projects above the block 29 and is fixed to the motor by cap screws 34. The plate 33 projects

below the block 29 and is fixed to the adjacent end of cradle 28 by bolts 35.

Below the motor 25 is an ignition transformer 36 (Figs. 1 and 2) and this transformer is utilized as a closure for the circular opening 37 in the rear wall of chamber 20. The back wall 16 of supporting member 10 has formed thereon a vertically disposed hollow-cylindrical part 38 (Fig. 1) for receiving a hinge pin 39. The transformer 36 is secured by two cap screws 40 (Fig. 3) to a plate 41. Each cap screw has a washer 40' between its head and plate 41. The plate 41 has upper and lower vertically spaced parts 42 which extend beyond one end of the transformer and are rolled up into hollow cylindrical form to receive the hinge pin 39. The adjacent ends of these parts 42 engage opposite ends of the part 38. The transformer is thus hinged to the supporting member 10. A hole 43 (Figs. 1 and 3) is formed in wall 16 adjacent the hinge described and so located as to receive and closely fit the washer 40' of that cap screw 40 which lies nearest to the hinge connection. Opposite such connection, a recess 44 is formed in the wall 16 for the purpose of receiving and closely fitting the washer 40' of the other cap screw 40. When the transformer is moved to the tube-closing position shown in Fig. 3, one of the washers 40' enters the hole 43 and the other the recess 44 to accurately locate the transformer in the desired position. To releasably hold the transformer in such position, a spring latch 45 (Fig. 3), fixed at one end by screws 46 to member 10, has its other end formed to engage over the protruding end 47 of plate 41. The transformer has two high tension terminals 48, each supported by an insulator 49.

Within the air tube 23 is an assembly, which is quickly and conveniently removable through the outer end of the tube, when the plate 41 is unlatched and swung into tube-opening position. This assembly is releasably held in place in the tube by a knurled nut 50 on stud 51, the latter being engaged in an open-ended slot 52 (Fig. 2), formed in the lowermost part of wall 15 at the extreme lower end of chamber 20. When the nut 50 is loosened, the assembly, which includes the air directors, oil nozzle, and associated parts, together with the ignition electrodes, may be pulled back out of tube 23 for cleaning, inspection, or repair.

This assembly includes a cup-shaped body member (Fig. 2) having a circular back wall 53 and a circular flange 54. The back wall has hollow hubs thereon—one coaxially located hub in which a rigid oil pipe 55 is fixed in a manner to allow axial adjustment (see Fig. 3), and two hubs which lie above the first hub and in which are mounted in a manner to allow axial adjustment of the insulators 56 that support the ignition electrodes 57. The oil pipe 55 is connected by a flexible pipe 55' to the outlet of oil pump 26. Each electrode is attached to a conducting rod 58, which extends axially through the insulator and is threaded into a metallic piece 59 of hollow cylindrical form. The piece 59 carries a spring-pressed metallic pin 60. When the transformer 36 is swung into tube-closing position, the terminals 48 of the transformer engage, one with each of the contact pins 60 and thereby connect the transformer terminals to the electrodes.

The oil pipe 55 carries on its inner end a suitable atomizing nozzle, such for example, as the pressure atomizing nozzle 61. The invention, however, does not depend on the type of nozzle 75

used and other suitable types may be used as desired.

The air forced forwardly in tube 23 by the fan is spread outwardly by the back wall 53 and forced to travel forwardly in the annular space between the inner wall of tube 23 and the outer wall of a barrel 62. This barrel—a hollow cylindrical sleeve made up of sheet metal—contains one or more sets of air directors. The barrel is suitably fixed at its inner end, as by a press fit, to the flange 54, and at its forward end abuts the inner face of a rounded deflector 63, fixed in any suitable way to the inner end of air tube 23. Fixed in the inner end of barrel 62 is a deflector 64 having a rounded end projecting beyond the deflector 63 and having also a cylindrical portion which fits in the opening of the deflector 63 and serves to centralize and support the barrel 62 at its inner end. The outer end of the barrel is supported by a pair of axially-spaced webs 65, the lower edges of which are curved to fit the inner periphery of the air tube 23 and rest thereon as shown in Fig. 6. These webs 65 are interconnected by an integrally formed top wall 66 and the whole is connected to the back wall 53 by an integrally formed member 67 of T-shaped cross section.

The barrel 62 contains two sets of air directors. Either one of them may be used, independently of the other, or both may be used conjointly, as will later appear in detail. The first set of air directors is located forwardly in the air tube and at or about the same axial location as the oil nozzle 61. These directors comprise a circular series of openings 68 in barrel 62 and a series of curved deflectors 69, one for each opening. Preferably there are a substantial number (16 as shown) of these openings. The deflectors 69 are so formed as to cause the air to enter tangentially and whirl around the axis of the oil nozzle and, more particularly, about the fuel spray emitted therefrom. It is to be noted that the outer end edges of the deflectors 69 serve as limiting stops for the deflector 64 (Fig. 2). The second set of air directors is located rearwardly of the first set and comprises a circular series of openings 70. There are less of these openings (4 as shown) and each is larger than in the case of the openings of the first set. These openings 70 are intended to admit air, without whirling it, to the fuel spray.

Preferably, the interior of the barrel is provided with a nozzle-like partitioning member 72, suitably fixed, as by a press fit, in barrel 62 and having a frusto-conical portion 73 terminating in a cylindrical portion 74. This member 72 is so located as to prevent the air admitted through openings 70 from mixing with the whirling air admitted through openings 68 until at or near the exit 64 of the air tube. The whirled air, as shown, is kept outside and surrounds the air admitted through openings 70, but the arrangement could be reversed if necessary or desirable.

Each set of air directors has a control valve. As shown, each valve consists simply of a sheet-metal sleeve telescoped over, and slidably engaged with, the barrel 62. The valve for openings 70 is marked 76 and that for openings 68 is marked 76'. Each is operated in the same way by similar means and only one such means will be described; corresponding parts of the other means being marked by the same reference numerals with the addition of a prime. The sleeve 76 has suitably fixed thereto at its rear end, and near its lower part, an interiorly threaded lug 77. A rod 78 (Fig. 9), rotatably

supported in part in one of the webs 65 and in part in an ear 79 formed on support 53, has a threaded forward end which is engaged in the nut-forming lug 71. The rear end of rod 78 has fixed thereto a knurled head 80 having a central rounded protuberance which engages the rear web 65. A spring 81 acts between this knurled head and the front web 65 with a tendency to hold the protuberance engaged with the rear web. Any other suitable means of holding rod 78 against substantial axial movement may be used as desired.

The peripheral wall of chamber 20 is notched as at 82 and 82' (Fig. 6) to enable access for turning the knurled heads 80 and 80', and thus effecting adjustment of the two air valves, without moving the transformer on its hinges, and for that matter, without removing the hood 13. One can reach in under the burner tube, at a point between the posts 11, and turn these knurled heads as will be clear from Figs. 1 and 2.

The operation of the burner will next be described. On a demand for heat, the motor 25 is set in operation, thereby actuating the fan 24 and the oil pump 26. Oil is forced through pipes 55' and 55 to nozzle 61 and is emitted from the latter initially in the form of a substantially conical spray. Air from the fan is forced downwardly into chamber 20 and thence forwardly in tube 23 to issue through the air directors and supply the air for combustion of the fuel emitted from nozzle 61. The fuel mixture is ignited in any suitable way, as by a high tension spark between electrodes 57—energy for the same being supplied from transformer 36. The above is the usual operation common to all burners of this general type.

This invention is characterized by the provision of two sets of air directors, each having a different influence on the flame. Air admitted tangentially through the openings 68 and past the deflectors 69 is whirled and such air has the effect of broadening the flame. Such air, from the mode of its admission, has relatively little forward velocity left. Air admitted through the rear slots 70 has a free radial entrance and can pass forwardly inside the deflector 72, 73, 74, and acts with considerable forward velocity on the flame, tending to elongate and narrow the same. Since the air admitted through the two sets of directors has different influences on the flame, it is possible, by using the valve control provided, to admit more air through one director and less air through the other director and vary the shape of the flame throughout a wide range. For example, by closing all the openings 68 with valve 76 all the air will be admitted through the rear set of openings 70 and act with its forward velocity on the flame with a tendency to elongate it. An exceedingly long and narrow flame, almost pencil-like in shape, can be obtained in this manner. Now, if the rear slots 70 are all closed by the valve 76 and valve 76' is moved to fully open all the openings 68, then all the air admitted to the flame will whirl around the flame, creating turbulence and having almost no forward velocity, and the flame will be broadened out and shortened. In this manner, a flame having the shape of an umbrella is obtained. By opening both valves 76 and 76', the shape of the flame can be changed to various degrees between these two extremes. Of course, if one valve is opened more widely, then the other should be closed in proportion, with the

object of maintaining substantially constant the volume of air supplied to the flame.

It is to be noted that the arrangement for admission of the air through the periphery of the air head is productive of a more even distribution of the air around the circle of the fuel spray. If the air is unevenly distributed in tube 23, and it usually is, then the admission of air to the flame in a substantially axial direction would carry this non-uniform distribution of air to the flame and poor combustion would result. That is why the air, in many burners, is whirled. An improved distribution of air is secured by the turbulence created. Here, however, excellent uniformity of air distribution is secured by preventing any air from passing axially through the rear wall 53. All air is forced outwardly and into the annular space between the barrel 62 and tube 23 and thence inwardly through the peripheral wall of the barrel. An uneven distribution of air in tube 23 is greatly improved by the described arrangement. In the present burner, therefore, the whirling of the air is not particularly needed for the purpose of improving distribution. This is proved by the operation of the burner which on tests shows that there is relatively little difference in the efficiency of combustion whether the burner is operating with all air obtained through slots 68 or all air obtained through slots 70. There is a difference but it is not particularly great. Excellent combustion is obtained in either case and the whirling of the air has its chief value here in its broadening influence on the flame.

It is to be noted that all the adjustments for controlling the rate at which air is supplied to the burner, are on the pressure or discharge side of the fan. The inlet to the fan is never restricted. Air is drawn in at the maximum rate possible and the first restriction is at about the location where air is delivered to the burner. It follows that the air may be maintained at a much higher velocity up to its point of application and a much more effective whirling of the air produced, than if the rate of air supply were regulated, as is common prior practice at the inlet side of the fan.

The invention provides for convenient adjustment of the air control valves without disturbing any part of the burner. One can reach the knurled heads 80 and 80' without opening up the burner.

The invention also provides a convenient means of dismounting the air head with its valves and the oil nozzle and spark electrodes. One simply removes hood 13, disconnects pipe 55', swings transformer 36 on its hinge to fully open the rear end of chamber 20, then loosens nut 50, whereupon by an outward pull on the parts 65—66, the barrel 62 and all parts connected thereto may be withdrawn as a unit. One need not disturb the adjusted relation of the various parts. This assembly of parts may be replaced with the same ease and convenience. The assembly is thrust inwardly through hole 37 into tube 23 until the front end of barrel 62 strikes the deflector 63. This will locate the assembly in the correct position axially of tube 23. When the assembly is thus positioned, the deflector 64 will have passed into the hole in deflector 63 and thereby the forward end of the assembly will be accurately centered in the tube—the rear end being held up by the webs 65, which rest on the tube 23. The nut 50 is then tightened, the oil pipe 55' reconnected, the transformer 36 is

swung into closed position, and the hood 18 replaced, whereupon the burner is ready to be placed in operation again.

The present burner is exceptionally quiet in operation. Much of the spark noise has been prevented from being reflected back through air tube 23. The path for the sound to travel is a devious one and, as a result, much less noise is had from this source than heretofore.

The invention provides a burner which is characterized by its flexibility to meet the widely varying conditions encountered in service. The burner may be simply and quickly adjusted to vary the flame within wide limits to fit fireboxes of various shapes and sizes.

I claim:

1. In an oil burner, inner and outer spaced coaxially-disposed tubes, a closure for said space at one end of each of the tubes, a closure for the opposite end of the inner tube, the other end of the outer tube extending beyond the closed end of the inner tube, means for supplying air to the last-named end of the outer tube and forcing it forwardly therein into said space, the forward end of the inner tube being open, and a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one set of said openings being constructed to whirl the air around the fuel spray and the other set of openings being constructed to admit air radially without whirling.

2. In an oil burner, inner and outer spaced coaxially-disposed tubes, a closure for said space at one end of each of the tubes, a closure for the opposite end of the inner tube, the other end of the outer tube extending beyond the closed end of the inner tube, means for supplying air to the last-named end of the outer tube and forcing it forwardly therein into said space, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one set of said openings being constructed to whirl the air around the fuel spray and the other set of openings being constructed to admit air radially without whirling, and a nozzle-like member positioned coaxially of and within the inner tube, said member separating the air admitted through the first set of openings from that admitted through the second set of openings and directing the air admitted through the second set of openings forwardly in the direction of said spray.

3. In an oil burner, inner and outer spaced coaxially-disposed tubes, a closure for said space, at one end of each of the tubes, a closure for the opposite end of the inner tube, the other end of the outer tube extending beyond the closed end of the inner tube, means for supplying air to the last named end of the outer tube and forcing it forwardly therein into said space, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such

air uniformly around the axis of the inner tube, one set of said openings being constructed to whirl the air around the fuel spray and the other set of openings being constructed to admit air radially without whirling, and means for selectively controlling the air admitted into the interior of the inner tube, whereby all the air required may be admitted from either set of openings or partly from one set and partly from the other.

4. In an oil burner, inner and outer spaced coaxially-disposed tubes, a closure for said space at one end of the tubes, a closure for the opposite end of the inner tube, the other end of the outer tube extending beyond the closed end of the inner tube, means for supplying air to the last-named end of the outer tube and forcing it forwardly therein into said space, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one set of said openings being constructed to whirl the air around the fuel spray and the other set of openings being constructed to admit air radially without whirling, sleeve valves one for each set of openings and each telescoped over and axially slidable on said inner tube, and means controlled from the last-named end of the outer tube for operating said valves the one independently of the other.

5. In an oil burner, inner and outer spaced coaxially-disposed tubes, a closure for said space at one end of the tubes, a closure for the opposite end of the inner tube, the other end of the outer tube extending beyond the closed end of the inner tube, means for supplying air to the last-named end of the outer tube and forcing it forwardly therein into said space, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one such set comprising a series of openings relatively small in size and relatively large in number, for whirling the air, the other set comprising a series of openings relatively few in number and relatively large in size for admitting air radially without whirling.

6. In an oil burner, inner and outer spaced coaxially-disposed tubes, a closure for said space at one end of the tubes, a closure for the opposite end of the inner tube, the other end of the outer tube extending beyond the closed end of the inner tube, means for supplying air to the last-named end of the outer tube and forcing it forwardly therein into said space, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one such set comprising a series of openings relatively small in size and relatively large in number for whirling the air, the other set comprising a series of openings relatively few in number and relatively large in size for admitting air radially

without whirling, the last-named set located rearwardly of the first-named set.

7. In an oil burner, inner and outer spaced coaxially-disposed tubes, a closure for said space, at one end of each of the tubes, a closure for the opposite end of the inner tube, the other end of the outer tube extending beyond the closed end of the inner tube, means for supplying air to the last-named end of the outer tube and forcing it forwardly therein into said space, said supplying means having an unrestricted inlet for air, the forward end of the inner tube being open, a nozzle for emitting a fuel spray positioned in the open end of said inner tube, said inner tube having in its peripheral wall two axially-spaced sets of openings each adapted to admit air into the interior of the inner tube and distribute such air uniformly around the axis of the inner tube, one set of said openings being constructed to whirl the air around the fuel spray and the other set of openings being constructed to admit air radially without whirling, and means for selectively controlling the air admitted into the interior of the inner tube, whereby all the air required may be admitted from either set of openings or partly from one set and partly from the other, said selective control means constituting the only means for varying the rate at which air is supplied to the burner.

8. An oil burner, having in combination, a pressure atomizing nozzle having an orifice for emitting a substantially hollow conical spray of fuel, a first and a second means for directing air to the fuel spray, said two means constituting the only means for directing air to the fuel spray, said air-directing means having inlets and outlets, the outlets being located closely adjacent to each other and to the orifice of said nozzle and there being no communication between said two air-directing means at all locations between their inlets and outlets, a common supply conduit for and communicating with the inlets of both air-directing means, first and second valve means for respectively controlling communication between said conduit and the inlets to the first and sec-

ond air-directing means, said two valve means being operable the one independently of the other and each operable to vary or wholly shut off the flow of air to its air-directing means, one air-directing means constructed to direct all the air supplied to it in a direction substantially parallel with the axis of the fuel spray, the other air-directing means constructed to direct all the air supplied to it in a substantially spiral path whirling it around the fuel spray, said valve means enabling all the air required for combustion to be admitted through either of said air-directing means or partly through one means and partly through the other means.

9. An oil burner, having in combination a pressure atomizing nozzle having an orifice for emitting a substantially hollow conical spray of fuel, a first air director comprising a tube disposed coaxially of said orifice and arranged to direct all the air supplied to it in a direction parallel to the axis of said spray, a second air director comprising a circular series of fixed and substantially spiral vanes surrounding the nozzle in coaxial relation with said orifice and arranged to whirl all the air supplied to them around said axis, said tube and vanes having inlet and outlet passages, said tube preventing communication between the two air directors at all points between said inlet and outlet passages, said two air-directors constituting the only means for directing air to the fuel spray, both outlets being located in closely adjacent relation and closely adjacent to said orifice, a common supply conduit for both said air directors and with which the inlets of the directors may communicate, and separate and independently-operable valve means for separately controlling the air supply to each air director, each valve means operable to entirely cut off the air supply to its director when desired, said valve means enabling all the air required for combustion to be admitted through either one of said air directors or partly through one and partly through the other.

WARREN H. DE LANCEY.
